[57] ABSTRACT

A spark ignition system for a plurality of gas burners providing for operation of a plurality of spark ignition circuits from one a.c. source, with each of the ignition circuits having a voltage multiplier feeding a pulsing circuit which in turn provides ignition pulses to the ignition electrodes, with an isolation diode between the voltage multiplier and pulsing circuit of each ignition circuit.

SPARK IGNITER FOR A PLURALITY OF GAS BURNERS

BACKGROUND OF THE INVENTION

This invention relates to spark type igniters for gas burners which are used for automatically igniting the gas at a burner such as is used in furnaces, water heaters, clothes dryers and the like.

Typical prior art spark igniters are shown in U.S. Pat. Nos. 3,349,284; 3,377,125; and 3,662,185. U.S. Pat. No. 3,377,125 shows a conventional pulsing circuit energized from a transformer and providing a high voltage pulse across a pair of electrodes at the gas burner. The pulsing circuit generates the pulses which produce sparks between the electrodes causing ignition of the gas at the burner. U.S. Pat. No. 3,349,284 shows an earlier form of pulsing circuit. U.S. Pat. No. 3,662,185 shows the pulsing circuit of U.S. Pat. No. 3,377,125 energized by a voltage multiplier in the form of a voltage tripler.

It is preferable to operate the spark igniters from a low voltage ac source, typically by means of a step-down transformer with the primary connected to the 115 volt supply and with the secondary providing a 24 volt output. The 24 volt systems eliminate many wiring problems which must be handled using higher voltage systems. Also, it is often desirable to operate a plurality of the spark igniters from a single source, i.e., from a single step-down transformer. However problems are encountered when a plurality of the spark igniters are connected to a single ac supply. Common feedback paths are created between units and the resulting interaction causes the energy generated in the voltage multipliers to be continuously depleted. Accordingly, it is an object of the present invention to provide a new and improved spark ignition system particularly suited for operation with a plurality of gas burners from a single ac supply. A further object is to provide such a spark ignition system utilizing the conventional circuitry with a simple yet highly effective modification which prevents energy stored in one voltage multiplier from being depleted by operation of related pulsing circuits.

SUMMARY OF THE INVENTION

The spark ignition system of the present invention incorporates a plurality of spark ignition circuits with the inputs thereof connected together for energization from a single ac power source, typically a step down transformer secondary winding. Each of the spark ignition circuits may use a conventional voltage multiplier and a conventional pulsing circuit such as is shown in the prior art. The voltage multiplier may be a tripler but a quadrupler is preferred and illustrated herein. A unidirectional conducting device, typically a solid state diode, is connected in circuit between the voltage multiplier and the pulsing circuit in each of the spark ignition circuits.

BRIEF DESCRIPTION OF THE DRAWING

The single FIGURE of the drawing illustrates a spark ignition system for three gas burners and incorporating the presently preferred embodiment of the invention.

DESCRIPTION OF THE PREFERRED EMBODIMENT

Three spark ignition circuits 10, 11, 12 are connected to power supply terminals 13, 14, which typically may be energized from the secondary winding of a transformer. The circuits 10, 11, 12 are identical and each includes a voltage quadrupler 17 and a pulsing circuit 18, with the output of the pulsing circuit connected to the electrodes of a spark gap igniter 19.

The voltage quadrupler 17 includes a capacitor 21 connected between terminal 13 and junction 22, and another capacitor 23 connected between terminal 13 and junction 24. A diode 25 is connected between junctions 22 and 26, and another diode 27 is connected between junction 22 and terminal 14. A capacitor 28 is connected between the junction 26 and the terminal 14. A series combination of a diode 30 and a resistor 31 is connected between the junction 24 and the terminal 14, and another series combination of a diode 32 and a resistor 33 is connected between the junction 24 and a junction 34 which may be connected to circuit ground. The diodes 25 and 30 are poled for conduction in the same direction and the diodes 27 and 32 are poled for conduction in the opposite direction.

The output of the quadrupler 17 is developed across a capacitor 40 at junctions 41, 34 through another diode 42.

In the pulsing circuit 18, the primary winding 44 of a high voltage step up transformer 45 is connected in series with the anode and cathode of a controlled rectifier 46 across the junctions 41, 34. A resistor 47 is connected in series with a capacitor 48 at junctions 49 across the junctions 41, 34. A gas discharge device such as a neon lamp 52 is connected in series with resistors 53, 54 across junctions 49 and 34, with the control electrode of the controlled rectifier 46 connected to the junction 55 between resistors 53, 54.

In operation, the capacitor 40 is charged from the voltage multiplier, and the capacitor 48 is charged from the voltage multiplier through the resistor 47. When the charge on the capacitor 48 builds up to a predetermined value, the lamp 52 conducts, discharging the capacitor 48 through the resistors 53, 54 and raising the voltage at junction 55, firing the controlled rectifier 46 into conduction. When the rectifier 46 conducts, the capacitor 40 is discharged through the transformer primary 44, developing a high voltage pulse at the secondary 58 and providing a spark at the igniter 19.

The pulsing circuit continues to provide sparks at the igniter until gas is ignited. The flame at the gap between the electrodes provides a low impedance path from junction 49 through the secondary 58 to circuit ground and prevents the capacitor 48 from charging to a value sufficient to fire the lamp 52 while the flame is present. If the flame goes out for some reason, the pulsing circuit automatically produces the sparks at the igniter.

There is interaction between a plurality of the spark igniters causing continuous depletion of energy from the voltage multipliers. This interaction is a result of the characteristics of the controlled rectifier (SCR) 46. The SCR is a bistable semiconductor which can be switched from off to on and from on to off. When the voltage between the anode and cathode of the device is below the breakover point, current through the SCR is extremely small and the device is effectively an open switch.

The SCR is turned on by the application of a current to the gate or control electrode of the SCR. The gate current has the effect of lowering the SCR breakdown point. Once breakdown point is exceeded, the SCR switches to its on state, and will remain on with no further application of gate current, until the current from anode to cathode drops below holding current. When current between anode and cathode drops below holding current, the SCR reverts back to its high impedance off state.

If a plurality of spark igniters are connected to a single step-down transformer, energy stored in capacitors 28 and 40 will transfer from one unit to another in such a way that a continuous holding current will be maintained on all SCR's. This causes them to remain on continuously. When these SCR's remain on continuously, capacitors 28 and 40 which act as reservoirs when the SCR's are in the off state, will not be permitted to store energy. Diode 42 which permits current to flow in one direction only, will prevent the energy transfer from one spark igniter unit to another, and therefore permit any SCR to turn off when the energy in capacitor 40 is depleted.

Typical values for the circuit may be:

21	10 microfarads
23	1 microfarad
28	4.7 microfarads
40	1 microfarad
48	0.0033 microfarads
25	IN4003
27	IN4003
30	IN4448
32	IN4448
42	IN4003
46	C106B1
31	1 kilohm
33	1 kilohm
47	51 megohms
53	1 kilohm
54	1 kilohm
52	60-80 volts
45	3000:1

I claim:

1. In an electric spark ignition system for a plurality of gas burners, the combination of:

a pair of power supply terminals for connection to an a.c. power source; and a plurality of spark ignition circuits, each comprising:

- 5 a voltage multiplier having input terminals connected to said power supply terminals and having multiplier output terminals,
- 10 a pulsing circuit having input terminals for connection to a voltage source and providing a pulse output to ignition electrodes of a gas burner, and electric circuit means connecting said pulsing unit input terminals to said multiplier output terminals with a unidirectional conducting device in circuit between one multiplier output terminal and the corresponding pulsing circuit input terminal.
- 15 2. A system as defined in claim 1 wherein each of said voltage multipliers is a voltage quadrupler.
- 20 3. A system as defined in claim 1 including three of said spark ignition circuits.
- 25 4. A system as defined in claim 3 wherein each of said voltage multipliers is a voltage quadrupler.
- 30 5. A system as defined in claim 1 wherein each of said voltage multipliers includes:
  - a first capacitor and a first diode connected in series at a first junction between one of said power supply terminals and said one multiplier output terminal,
  - 35 a second capacitor connected between said one multiplier output terminal and the other of said power supply terminals,
  - a second diode connected between said first junction and said other power supply terminal,
  - a third capacitor and a third diode connected in series at a second junction between said one power supply terminal and the other of said multiplier output terminals, and
  - 40 a fourth diode connected between said second junction and said other power supply terminal, with said first and fourth diodes and said unidirectional conducting device poled for conduction in the same direction and with said second and third diodes poled for conduction in the opposite direction.
